UNITED STATES PATENT OFFICE.

JACOB GOLDSTEIN AND ISRAEL BLOCK, OF NEW YORK, N. Y.

DESIGN FOR AN OIL OR GAS STOVE.

SPECIFICATION forming part of Design No. 20,503, dated February 3, 1891.

Application filed December 29, 1890. Serial No. 376,129. Term of patent 14 years.

To all whom it may concern:

Be it known that we, JACOB GOLDSTEIN and ISRAEL BLOCK, citizens of the United States, and residents of New York, in the county of New York and State of New York, have invented a certain new and useful Design 5 for Oil-Stoves; and we do declare the following to be a full, clear, and exact description of the invention, such as will enable others skilled in the art to which it appertains to make and use the same, reference being had to the accompanying drawings, and to letters of reference marked thereon, which form a part of this specification.

15 Figure 1 of the drawings is a top plan view. Fig. 2 is a side elevation.

The invention relates to certain new and original designs for gas-stoves; and it consists in the novel form and configuration 20 thereof herein shown and described.

In the accompanying drawings, A represents the base or support, which is of elongated elliptical form and having a surrounding flaring convex depending flange or fringe 25 extension B, formed of open or skeleton work and terminating at its lower edge in the scalloped rim a, having at each corner an extension or leg b, tapering downward and also of scalloped form. At the front the central 30 scallop a' of the rim a is shown as being of greater length and larger size than the remaining scallops. The top portion of the base or support A is shown as having near each end a circular opening C C, having arranged therein the circular rim D, which consists of a plain marginal horizontal flange c, having rising from its inner edge the flaring convex open-work portion E, terminating at its upper inner edge in the plain annular rim 35 E', surrounding a circular opening F. This portion E E' is shown as having a series of

radial plate-like vertically-disposed laterally-converging lugs G, their inner ends extending in over the circular openings F, as shown. Near their outer ends on their upper surfaces 45 these lugs are shown as having each an arc-shaped concavity or depression f, similar depressions f' being also shown near the inner ends of said lugs, but of smaller size. The lugs G converge over the circular plate H, formed 50 with a central annular uprising flange h.

The central top portion of the base or support A, between the circular openings C C, (shown at L,) is of open-work form, having the concave side edges l. A plain annular ring M is shown at the center of this portion, inside of which is a skeleton or open-work figure, as shown.

At the front side, near each corner, the base or support A is shown as having a solid plate-piece N, itself having the convex outwardly-projecting portion n, to which are connected the perforated pipe portions R, which are shown as of irregular circular flanged form and provided near their outer ends with handle angular projections P, of the form shown. 65

Connected to the outer ends of the portions R is the tubular portion S, terminating at one end in a knob s and having at its other end a series of flanges t, of annular form and surrounding a reduced portion w, as shown. 70

What I claim is—

The design for gas-stoves having the form and configuration herein shown and described.

In testimony whereof we affix our signatures 75 in presence of two witnesses.

J. GOLDSTEIN.
ISRAEL BLOCK.
